HANDKERCHIEF PACKAGE WRAPPER

Harry Steinberg, New York, N. Y.

Application May 28, 1948, Serial No. 146,667

Term of patent 14 years

(Cl. D59—2)

To all whom it may concern:

Be it known that I, Harry Steinberg, a citizen of the United States of America, residing in New York city, county of New York, and State of New York, have invented a new, original, and ornamental Design for a Handkerchief Package Wrapper, of which the following is a specification, reference being had to the accompanying drawing, forming part thereof, wherein:

I claim:

The ornamental design for a handkerchief package wrapper, substantially as shown.

HARRY STEINBERG.
